UNITED STATES PATENT OFFICE

109,181

DESIGN FOR A CLINCH-NUT MACHINE

Plummer E. Double, Detroit, and Frank Wascher,
Flint, Mich.

Application December 19, 1936, Serial No. 66,664

Term of patent 14 years

To all whom it may concern:

Be it known that we, Plummer E. Double and Frank Wascher, citizens of the United States, residing in the city of Detroit, county of Wayne, and in the city of Flint, county of Genesee, respectively, in the State of Michigan, have invented a new, original, and ornamental Design for a Clinch-Nut Machine, of which the following is a specification, reference being made to the accompanying drawing, forming part thereof.

Fig. 1 is a front elevation of a clinch-nut machine embodying our new design.

Fig. 2 is a side elevation of our machine.

We claim:

The ornamental design for a clinch-nut machine as shown.

PLUMMER E. DOUBLE.
FRANK WASCHER.
